UNITED STATES PATENT OFFICE.

SEXTUS A. EDDINS, OF BROCKTON, MASSACHUSETTS.

GARMENT CLASP AND METHOD OF MAKING SAME.

Application filed January 2, 1925. Serial No. 110.

To all whom it may concern:

Be it known that I, SEXTUS A. EDDINS, a citizen of the United States, and resident of Brockton, in the county of Plymouth and

5 State of Massachusetts, have invented an Improvement in Garment Clasps and Methods of Making Same, of which the following description, in connection with the accompanying drawings, is a specification, 10 like reference characters on the drawings representing like parts.

My present invention relates to novel garment clasps and to a novel method or process of making the same.

15 One of the principal difficulties found in the present types of clasps, such as used on garment and hose supporters, is that the holding devices engaging or clasping the garment to be supported, become too easily unfastened. An important object of my present invention, therefore, is to provide a garment clasp which, when in position on a fabric of any kind, will be positively held against accidental loosening, and will hold 20 the garment in a firm, tight grip at all times. I accomplish this desirable result by having the garment clasp constantly under tension when in clasping position. This tension may be provided in many ways, and I have 25 herein illustrated two preferable methods.

Garment supporters, particularly hose supporters including the clasps of the present application are shown, described and claimed in my prior and accompanying application Serial No. 757,020, filed December 35 19th, 1924. The present application is restricted to the clasps themselves, and to the process of making same.

In one form of clasp, as herein shown, I 40 so position one end of the garment clasp under a retaining strip, which strip is attached to a supporting plate, that when the clasp is in cooperative position on the garment holding button, it will be firmly held 45 against accidental loosening or unlocking movement.

As a second method of maintaining my improved clasp under tension, I utilize a strip of elastic webbing attached to one end 50 of the garment clasp, and so arranged as to exert a locking tension upon the garment holder at all times, and performs substantially the same function as the first construction above mentioned. In the manufacture 55 of my novel clasps I utilize non-metallic material, such as celluloid, or the like, so

far as feasible and practical, so as to eliminate the use of any metallic portion in the construction thereof.

A further feature of my present invention is that, all working parts of the same being composed of non-metallic material, the danger of tearing or otherwise injuring the fabric held by this clasp is eliminated.

I have also devised a garment clasp which is extremely economical to manufacture, for the reason that all of the operating parts of same can be stamped out of plate, or other sheet material. Thus, in utilizing celluloid, for example, the clasp, main plates, and other parts, can all be stamped out of celluloid plate at a single stamping operation.

I have also devised a novel button, preferably of rubber, or other resilient and non-metallic material, which button comprises a head, a neck, and a base, the base of this button being made considerably larger than the ordinary button base. The advantage of thus constructing my novel button in this manner is that the head and neck of the same may be "offset" or eccentric relatively with the base, if desired, and will give a better leverage for the base on the portion against which it rests, and will permit a greater strain to be placed upon the button, with less danger of its being broken away. I believe that my novel clasps, constructed as above described, are new and the same are claimed broadly herein.

In the manufacture of the first form of clasp above-mentioned, I utilize a supporting plate, to which is to be attached a retaining strip. At one end of the plate and strip are formed apertures, each larger at one end than the other, and having the larger portions of said apertures oppositely arranged in the plate and strip. In assembling the plate strip and button, the strip is positioned on the plate, in any such manner that the larger portions of the apertures are positioned over each other, whereupon the head and neck of the button are inserted therethrough, after which the strip is moved to normal position and secured to the supporting plate. This action of moving the strip to locked position after the insertion of the button, brings the smaller portions of the cooperating apertures in the supporting plate and strip, into alignment on the neck of the button, thus firmly gripping the same and preventing any possible looseness thereof. Before securing the strip to the sup-

porting plate, the garment clasp having therein an aperture preferably squared, is positioned between the plate and the strip, in such a manner that the strip projects 5 through the squared aperture. The purpose of this is that when the strip is secured to the supporting plate, it will at all times exert a downward holding tension on the garment clasp. The clasp is also provided 10 with the usual aperture or opening to fit over the button and garment held thereby, this latter opening being larger at one end than at the other, as will be hereinafter more fully described.

15 In forming the second clasp mentioned above, I provide a supporting plate, with an aperture at one end thereof, and thereupon split the end of the plate having the aperture, from the extreme end thereof to a pre-determined point beyond the aperture, whereupon, the material of which the plate is formed being flexible, the end of the plate is "sprung" where split, and the button inserted therethrough, whereupon on releasing 20 the split end, the same will firmly grip the button in position. The base of the button can also be cemented to the supporting plate in each of the above forms, if desired.

25 In this second form of clasp, the garment clasp is held to the supporting plate by a strip of elastic material, said clasp having therein a button engaging aperture similar to that above described. When the garment clasp has been placed in position over the button, the elastic retaining or holding strip will promptly bring the clasp into locking 30 position over the button. I believe that the process of manufacture of my novel garment clasp as above described is new, and the same is also claimed broadly herein.

35 Further features of the invention, novel combinations of parts, and advantages, will be hereinafter more fully pointed out and claimed.

40 Referring to the drawings, illustrating preferred embodiments of my present invention,

45 Fig. 1 is a front elevation of the supporting plate of my novel clasp;

50 Fig. 2 is a front elevation of the retaining strip;

55 Fig. 3 is a front elevation of the novel form of button used in my clasp;

Fig. 4 being a side elevation of the same button;

Fig. 5 is a front elevation of the plate, button and retaining strip in assembled position, just prior to being forced into completed position;

60 Fig. 6 is a cross-sectional view on the line 6—6 of Fig. 5;

Fig. 7 being a view on the line 7—7 of Fig. 5;

Fig. 8 is a front skeleton elevation of my 65 novel clasp in completely assembled form,

showing a garter to which it is attached, in fragmentary form;

Fig. 9 is a side sectional view on the line 9—9 of Fig. 8; and

Fig. 10 is a cross-sectional view on the line 10—10 of Fig. 9;

Fig. 11 is a fragmentary perspective view of the clasp and elastic retaining strip of a modification of my clasp; and

Fig. 12 is a perspective view of the supporting plate, and split end, of said modification.

As shown in the drawing, I provide a plate 1, having therein longitudinal slots 2, 2, through which the webbing of the leg band is fitted, and having also a small circular aperture 3, through which is clinched a rivet, or the like, as will be hereinafter described. On the lower end of the plate 1 is formed an aperture 4, preferably larger 80 at one end than the other. This plate 1 and all cooperating parts are made of non-metallic material. To this plate 1 is applied a strip 5, having therein a small circular aperture 6 to be alined with the aperture 3 85 in the plate 1, to receive a rivet, or the like, therethrough. At the lower end of this strip 5 I provide an aperture 7, also larger 90 at one end than the other. This aperture 7 is adapted to cooperate with the aperture 4 95 in the plate 1, and it will be noted that the larger ends of the apertures 4 and 7 are oppositely positioned. This strip 5 is also provided with slanting shoulders 8 and 9, the purpose of which I will describe here- 100 after.

Figs. 3 and 4 illustrate my novel form of button, comprising a base 10, neck 11, and head 12. It will be noted that the base 10 is larger than the usual or customary button 105 base, and that the neck and head of the button are "offset" or eccentric relatively with the center of the base. The purpose of so forming my novel button is that when the button is applied to an article, it will be capable of standing much greater strain and wear, due to the increased area and the bearing surface resulting therefrom, on the article to which it is applied.

Referring now to Fig. 5, this illustrates 115 the plate 1, strip 5, and the button, in assembled position, prior to being fitted in final position. As therein illustrated, the plate 1 and strip 5 have been superimposed on each other with the larger ends of the 120 apertures 4 and 7 in alinement, the head 12 of the button has been forced therethrough, and the strip 5 is ready to be moved upwardly along the plate 1, until the aperture 6 will have been brought into alinement 125 with the aperture 3 in the plate 1.

Figs. 6 and 7 are cross-sectional views illustrating the relative positions of the various members shown in Fig. 5, before being moved to final position.

As shown in Fig. 8, my novel clasp is illustrated in completely assembled and closed position. In this figure I have represented in fragmentary form, a conventional garter 5 or leg band 15, which is fitted through the slots 2 in the plate 1, and secured in position by a hooked rivet 16, which hooked rivet extends through the webbing 15 and apertures 6 and 3 in the strip 5 and plate 1 10 respectively, thus securing these portions of the clasp together in a firm and rigid manner. In this figure, also, is illustrated the clasp 20, having therein a squared aperture 21, this clasp being slidably mounted on the strip 5, which strip 5 extends through the aperture 21, and this strip 5 being firmly secured to the plate 1, at each end thereof, exerts a downwardly holding tension on the end 22 of the clasp 20. The clasp 20 is also 15 provided with an aperture having an enlarged portion 23, and a narrow portion 24. When the clasp is in closed position, upon the button 12, the narrow end 24 of this aperture fits snugly about the neck 11 of said button, and the garment or fabric held thereover. This clasp 20 is also held firmly in position, against accidental loosening or unfastening by the tension of the strip 5 thereon. When it is desired to unfasten 20 the garter, as shown herein, the clasp 20 will be moved downwardly, as shown in Fig. 8, until the enlarged portion 23 is in alinement with the head 12 of the button whereupon the sides of the squared aperture 21 will 25 come in contact with the slanting shoulders 8 and 9 of the strip 5, thus forcing the lower end of the clasp 20 upwardly and away from the button, and fabric held thereon, insuring a positive freeing of the clasp from said button and fabric.

Fig. 9 is a cross sectional view, clearly illustrating the assembled structure shown in Fig. 8, and illustrates graphically the pressure or tension exerted upon the end 22 45 of the clasp 20.

Fig. 10 is a cross-sectional view on the line 10—10 of Fig. 9, clearly illustrating the gripping action of the strip 5 and plate 1 upon the neck 11 of the button, when the 50 parts are in the position illustrated in the Figs. 8 and 9.

Referring now to Figs. 11 and 12, illustrating a modification of my present clasp wherein I have provided a supporting plate 30, having therein slots 31, 31, similar to slots 2, 2 in Fig. 1, and having also a circular aperture 32 similar to and for the same purpose as the aperture 3 in Fig. 1. This plate 30 is provided at one end thereof 55 with an aperture 32^a, and is also split along a portion thereof, as illustrated at 33. When applying the garment holding button thereto, the split end 33 is forced apart, the head 34 and neck 35 of the button are wedged 60 therethrough, whereupon the slit end 33

is returned to normal position firmly gripping the neck of the button therein. The button herein illustrated is also provided with an enlarged base 35, for greater resistance and holding capacity. I also provide a clasp 36, having therein a button receiving aperture, this aperture having an enlarged end 37, and a narrow end 38. At the opposite end of this clasp I also provide a slot 39, through which is fitted a strip of 70 elastic webbing or the like 40, this strip 40 being stitched together or otherwise secured at 41. This elastic webbing 40 is secured at the other end, by a hooked rivet (not shown), which secures the leg band webbing 40, and plate 30 together, passing through the aperture 32 in the plate 30. It will thus be seen that, upon application of the clasp 36 to the button 34, through the enlarged portion 37 of the aperture in the 75 clasp, upon release of the clasp 36, the tension of the elastic webbing or other elastic material will automatically pull the clasp 36 upwardly or to the left, as viewed in Fig. 12, until the narrow portion 38 of the aperture engages with the neck 35 of the button 34 and the fabric which is on the button, thus holding the same at all times in a firm manner, and preventing accidental loosening or unclasping of the same.

I believe that my novel clasps, as above illustrated and described, are new, and also the processes of making same, and I desire to claim these broadly herein.

While I have described my invention somewhat in detail, it will be appreciated that I may vary the size, shape and arrangement of parts within wide limits, without departing from the spirit of the invention.

My invention is further described and defined in the form of claims as follows:

1. A clasp of the kind described comprising a body portion having a resilient button attached at its lower end and extending through and outwardly therefrom, said button being set eccentric relatively with its base, a resilient retaining strip secured to said body portion a clasp member slidably mounted between said body portion and said resilient retaining strip, said clasp member being provided with a perforation and adapted to fit over the button, whereupon it will be held under constant tension by the pressure of the resilient strip.

2. A clasp of the kind described comprising a body portion and a resilient retaining strip, cooperating oppositely positioned apertures in said body portion and strip, said apertures being adapted to receive and hold a button, said button being set eccentric relatively with its base, a clasp member slidably mounted between said body portion and said resilient retaining strip, said clasp member being provided with a

- perforation and adapted to fit over the button, whereupon it will be held under constant tension by the pressure of the resilient member.
5. 3. A clasp of the kind described comprising a body portion and a resilient retaining strip, cooperating oppositely positioned apertures in said body portion and strip, said apertures being adapted to receive and hold a button, said button being set eccentric relatively with its base, a clasping member slidably mounted between said body portion and said resilient retaining strip, said clasping member being provided with a 10 perforation and adapted to fit over the button, whereupon it will be held under constant tension by the pressure of the resilient member, and means on the retaining strip to automatically move the clasping member 15 away from the button when said clasping member is moved toward unclasping position.
- 10 20
4. A clasp of the kind described comprising a body portion and a resilient retaining strip, cooperating oppositely positioned 25 apertures in said body portion and strip, said apertures being adapted to receive and hold a button, said button being set eccentric relatively with its base, a clasping member slidably mounted between said body portion and said resilient retaining strip, said 30 clasping member being provided with a perforation and adapted to fit over the button, whereupon it will be held under constant tension by the pressure of the resilient member, and inclined shoulders on the retaining strip to automatically move the clasping member 35 away from the button when said clasping member is moved toward unclasping position.
- 40

In testimony whereof, I have signed my name to this specification.

SEXTUS A. EDDINS.
